UNITED STATES PATENT OFFICE.

AUGUST HEINE, OF SILVER CREEK, NEW YORK.

FLOUR-BOLT.

SPECIFICATION forming part of Letters Patent No. 355,526, dated January 4, 1887.

Application filed May 11, 1886. Serial No. 201,848. (No model.)

To all whom it may concern:

Be it known that I, AUGUST HEINE, of Silver Creek, in the county of Chautauqua and State of New York, have invented a new and useful Improvement in Flour-Bolts, of which the following is a specification.

This invention relates to that class of flour-bolts which are provided on the inner side of the bolting-cloth with ribs or similar contrivances, whereby the material is elevated until the gradually-increasing angle of the rib causes the material to run off from the rib against a deflecting board or strip, which is arranged opposite the inner side of the elevating-rib, and whereby the material is deflected outwardly, or toward the bolting-surface.

The object of my improvement is to increase the efficiency of this class of flour-bolts, and to render the same simple and durable in construction.

My invention consists, to these ends, of the improvements which will be hereinafter fully set forth, and pointed out in the claims.

In the accompanying drawings, Figure 1 is a longitudinal sectional elevation of my improved flour-bolt. Fig. 2 is a cross-section of the same. Fig. 3 is a cross-section of one of the longitudinal ribs and connecting parts on an enlarged scale. Fig. 4 is a fragmentary longitudinal section of one of the end heads of the bolt. Fig. 5 is a fragmentary longitudinal section of the central ring of the bolt.

Like letters of reference refer to like parts in the several figures.

A represents the inclosing-casing, which may be of any suitable or well-known construction.

b represents the shaft of the bolt or reel, journaled in bearings B B, secured to the casing A.

C represents the head at the feed end of the bolt, secured to the shaft b, and provided on its outer side with a feed-cone, D, which receives the material to be bolted from a feed-spout, d.

E represents the head at the discharge end of the bolt, provided with a central discharge-opening, e, for the tailings, and carrying on its inner side elevating-ribs f and a deflecting-cone, f', for discharging the tailings through the opening e, in a well-known manner, into a discharge-spout, f'.

The heads C and E are provided, respect-

ively, with inwardly-turned marginal flanges g, to which the ends of the bolting-cloth H are secured.

I represents the longitudinal ribs which connect the heads C and E on the inner side of the bolting-cloth, and which are arranged at a short distance from the inner surface of the bolting-cloth, so as to leave spaces or passages i between the outer edges of the ribs and the bolting-cloth, through which the material can pass in flowing over the bolting-surface. These spaces are formed by studs or short posts j, which are secured to the outer edges of the ribs I, and which carry the rings f³, 65 against which the bolting-cloth rests.

K represents the deflecting boards or plates arranged opposite the inner edges of the ribs I, and separated therefrom by spaces or passages k, through which the material flows from one rib to the rib next below. These spaces are formed by studs or short posts l, which are secured to the inner edges of the ribs I, and to which the deflecting-plates K are secured by bolts m. The latter pass, preferably, 75 also through the studs j and rings f³, as represented in Fig. 3, thereby securing all of these parts to the ribs I.

N represents inclined fan-blades secured to the shaft b within the reel, preferably near the discharge-head E, and inclined sharply to the axis of rotation in such manner as to cause a slow movement of the air through the reel from the feed end to the discharge end thereof, thereby assisting in the removal of the light 85 floating specks, &c., through the discharge-opening e of the head E.

The bolting-cloth H is composed of two sections, h h', secured with their outer ends respectively to the heads C and E, and with their inner ends to the central ring, J, which is made somewhat wider than the rings f³, for the purpose of securing the bolting-cloth. The ring J is provided with two peripheral rows of sharp-pointed teeth or pins, o o, to which the bolting-cloth sections h h' are attached by fastening the strips p p', of ticking or other strong material, on these pins, as represented in Fig. 5. These strips are provided with cords q q', which are sewed between two thicknesses of the strip, which latter are doubled back to receive the cords, whereby the cords are located

at the extreme inner edges of the sections $h h'$, and serve to re-enforce these edges. In applying the strips $p p'$ to the teeth $o o$ the cords are placed on the inner sides of the rows of teeth, so that the strain which is applied to the bolting-cloth in stretching the same tends to draw the cords against the teeth, thereby securely holding the strips in place on the ring

J. The outer edges of the sections $h h'$ are also respectively provided with strips $r r'$, of ticking or other strong material, which are fastened to the heads C and E by tacks s after the cloth has been properly stretched. When the heads C and E are constructed of metal, the flanges $g g$ of the same are provided on their outer sides with rings $t t$, of leather or other suitable material, into which the tacks can be driven.

The material which is being bolted is elevated in part by the ribs I and gradually discharged by the same against the deflecting-plates K, and passes from these to the ribs I below, and then against other deflecting-plates K, whereby the material is broken up, disintegrated, or dashed in such manner as to liberate the light fluffy impurities, while the heavier particles pass in comparatively thin streams through the spaces i and k , opposite the outer and inner edges of the ribs, and over the bolting-cloth, whereby the operation of bolting is greatly facilitated and expedited. The light floating impurities pass through the spaces between the deflecting-boards K, into the inner space of the reel, which is comparatively undisturbed, and in which they pass slowly toward the discharge-opening e, through which they finally escape from the reel. This movement of the floating material in the direction of the axis of the reel is to a large extent due to the action of the inclined fan-blades N, which cause a gentle air-current to pass through the reel in the direction of its length and insure the removal of the floating impurities.

45 I claim as my invention—

1. In a rotary flour-bolt, the combination, with the bolting-surface H, of the elevating-ribs I, separated by spaces i from the bolting-surface, and deflecting-plates K, arranged opposite the inner edges of the ribs I, separated therefrom by spaces k , and constructed with unobstructed outer faces opposite the elevating-rib, whereby the material is enabled to pass freely from an elevating-rib to its deflecting-plate, and from the latter to the elevating-rib below, substantially as set forth.

2. In a rotary flour-bolt, the combination, with the bolting-surface H, of the elevating-ribs I, provided on the inner edges with studs l , and separate deflecting-plates K, secured to said studs, whereby spaces are formed between the plates K and the elevating-ribs, as well as between the several deflecting-plates K, substantially as set forth.

3. In a rotary flour-bolt, the combination, with the bolting-surface H, of the elevating-ribs I, provided on their outer edges with studs j , upon which the bolting-surface is supported, and on their inner edges with studs l , separate deflecting-plates K, applied to the studs l , and fastening-bolts m , passing through the ribs I, studs j and l , and deflecting-plates K, substantially as set forth.

4. The combination, with a rotary flour-bolt, of short fan-blades inclined sharply to the axis of rotation, secured within the bolt and rotating therewith, whereby an air-current is caused to flow lengthwise through the bolt, substantially as set forth.

5. The combination, with a rotary flour-bolt provided with longitudinal elevating-ribs I and deflecting-plates K, of inclined fan-blades secured within the bolt, substantially as set forth.

6. The combination, with a rotary flour-bolt composed of a shaft, b, heads C E, elevating-ribs I, deflecting-plates K, and a bolting-cloth, H, of fan-blades N, secured to the shaft b between the heads C and E, substantially as set forth.

7. The combination, with a rib, I, of the studs j and l , applied, respectively, to the outer and inner edges of said ribs, a ring, f^3 , resting on the outer stud, j , a deflecting-plate, K, resting against the inner stud, l , and a fastening-bolt, m , passing through the ring f^3 , stud j , rib I, stud l , and plate K, substantially as set forth.

8. The combination, with the end heads, C and E, and the central ring, J, provided with two peripheral rows, $o o$, of sharp pins, of two sections of bolting cloth, $h h'$, having their inner edges re-enforced and attached to the pins $o o$ and their outer edges tacked to the heads C and E, substantially as set forth.

Witness my hand this 5th day of May, 1886.
AUG. HEINE.
